UNITED STATES PATENT OFFICE.

HARRY J. LICHTENBERGER, OF WASHINGTON, DISTRICT OF COLUMBIA.

DESIGN FOR A SCARF-PIN OR SIMILAR ARTICLE.

No. 39,396.

Specification for Design.

Patented July 7, 1908.

Application filed May 4, 1908. Serial No. 430,874. Term of patent 7 years.

To all whom it may concern:

Be it known that I, HARRY J. LICHTENBERGER, a citizen of the United States, residing at Washington, in the District of Columbia, have invented a new, original, and ornamental Design for a Scarf-Pin or Similar Article, of which the following is a specification, reference being had to the accompanying drawing, forming part thereof.

The figure is an elevation of a scarf-pin or similar article, showing my design.

I claim:

The ornamental design for a scarf-pin or similar article, as shown.

HARRY J. LICHTENBERGER.
